LAPPING APPARATUS

David A. Wallace and Edward C. Lee, Detroit,
Mich., assignors to Chrysler Corporation,
Highland Park, Mich., a corporation of Dela-
ware

Application November 8, 1937, Serial No. 173,292

3 Claims. (Cl. 51—34)

This invention relates to improved apparatus for lapping internal cylindrical surfaces.

More particularly, the invention pertains to improvements in the apparatus for lapping internal surfaces of internal combustion engine cylinders, bearings and the like.

One of the main objects of the invention is to provide lapping apparatus by which the lapping elements may be expanded and urged by a pre-determined lapping pressure toward and contracted away from the work during normal operation of the lapping apparatus.

Another object of the invention resides in the provision of an apparatus of this character by which this expanding and contracting movement of the lapping elements is imparted by a non-rotating piston through a novel connection to the rotating and reciprocating elements of lapping apparatus in response to the admittance of fluid pressure, preferably air pressure, to act on the piston.

A further object of the invention resides in the provision of apparatus of this character by which the lapping tool may be reciprocated at a speed of substantially vibratory order while at the same time reciprocated at a slower speed and throughout a longer course and rotated about an axis extending substantially parallel to the course of said reciprocatory movements, and by which the means for holding the lapping elements may be selectively adjusted to expand or contract the lapping elements during any portion of the rotative or reciprocatory movements of the lapping elements.

A still further object of the invention is to provide a lapping apparatus of this character by which the machine formed grooves and ridges of the surface operated upon can be removed without producing lapping formed surface scratches.

Other objects and advantages of the invention will be more apparent from the following description taken in connection with the accompanying drawing, in which:

Fig. 1 is a fragmentary side elevational view of a lapping machine embodying the invention, portions of the structure being broken away and illustrated in section to show the details thereof.

Fig. 2 is a fragmentary vertical sectional view of the rotative and reciprocatory lapping tool adjusting and operating structure of the lapping apparatus shown in Fig. 1, portions of said structure being illustrated as broken and arranged in side by side adjacency rather than in alignment as in the actual apparatus.

Fig. 3 is a horizontal sectional view taken on line 3—3 of Fig. 2.

In the form of the invention illustrated in the drawing, the improved lapping apparatus comprises a base structure, generally designated by the numeral 5, having horizontal and vertical portions 6 and 7 respectively. The horizontal portion 6 has on its upper face a pair of parallel guideways 8 for conveniently guiding the work into lapping receiving relationship with the lapping apparatus, as will presently be more apparent.

The work, generally designated by the reference character 9, is illustrated as comprising a motor block having vertical cylinders to be lapped, but surfaces of other devices may be conveniently lapped without departing from the scope of the invention. A work carrier member 10 is adapted to support the work 9 on the guideways 8, and includes a pair of lower recesses 11 which register with the guideways 8. The carrier 10 further includes a plurality of locating pins 12 adapted to register with certain portions of the lower face of the work 9, and side arms 13 which centrally position and maintain the work 25 on the guideways 8.

A vertically reciprocable carriage 14 is slidably mounted on the vertical portion 7 of the base structure 5, the carriage having a web portion 15 guidable vertically within a channel forming member 16 detachably secured by bolts 17 to the portion 7. The carriage 14 further comprises an extension member 18, which extends through a vertical elongated slot 19 in the portion 7 and which is adapted to be adjustably positioned by a piston (not shown) operating within a fluid pressure cylinder 20 supported by the portion 7. One extremity of a piston rod 21 is fixed to the piston in the cylinder 20 and its other extremity is detachably secured to the extension member 18 by a bolt 22. The interior of the cylinder 20 is communicatively connected with a source of fluid pressure, preferably air pressure, by conduits 23 and 24 which, under the control of suitable automatic or manual valve mechanism (not shown) applies fluid under pressure to either end of the cylinder 20 so as to adjustably or operatively move the tool carriage 14 vertically.

A split casing 25 is detachably secured to the carriage 14 by bolts 29. This casing houses a suitable motor (not shown) for rotating a vertically and reciprocably carried lapping tool, generally designated by the numeral 30, which is carried by a tool holding and operating struc- 55

ture 30'. The lapping tool operating structure includes a tubular shank portion 31, having a threaded end and enlarged portions 31^a and 31^b respectively, and is rotatably and axially reciprocably mounted on the casing 25. A gear 33 (best shown in Figs. 1 and 2) is non-rotatably keyed to the section 31^a of the shank 31 at 32', there being provided in the shaft section 31^a an elongated keyway 32 for accommodating reciprocatory movement of the shaft relative to the gear 33. A pair of thrust ball bearings 34 and 35 surround and rotatably support the shaft portion 31 and they are disposed between the opposite sides of the gear 33 and thrust bearing collars 37 and 38 mounted in apertures in the portion 27 of the casing 25. The members 37 and 38 together with the bearings 34 and 35 prevent the gear 33 from moving axially relative to the casing 25. A drive shaft 39 is journaled by a bearing block 40 detachably secured to the portion 26 by bolts 41, and has keyed thereto at 42 a worm gear 43 which is in mesh with the gear 33. The shaft 39 receives its drive from the aforesaid motor housed within the casing 25, and is adapted to be driven while the tubular shaft portion 31 is reciprocated relative to the carriage 14 by structure hereinafter set forth.

The enlarged portion 31^b of the tubular shaft 31 comprises recessed and threaded counterbore portions 44 and 45 respectively and has formed thereon a socket recess 46 in which is received a ball portion 47 of a tubular link member 48, the ball portion 47 being pivotally connected to the portion 31^b. A washer 50 is received within 35 in the recess 44 on the outer side of the ball portion 47 and is detachably secured therein by a threaded member 51 which threadedly engages the portion 45.

Formed on the tubular member 48, as illustrated in Fig. 2, is a threaded aperture 52 which receives a pair of hemisphere shaped members 53 having apertures 54 aligned with the aperture 52 through which bolts 55 are threadedly engageable with the member 48.

45 A tubular lapping element holder 56 has a substantially spherical socket portion 57 and recesses 58 to receive the members 53 and 48, and the heads of the bolts 55 respectively. A recessed threaded portion 59 of the holder 56 is axial alignment with and of substantially the same diameter as the recesses 58 admit the members 53, and bolts 55, the recesses 58 preventing rotation of the tubular member 48 relative to the holder 56, and permitting a slight amount of pivotal movement of the member 48 and holder 56 for the centering action of the holder when the work 9 is in lapping receiving relation, as will hereinafter be more apparent. The holder 56 also has an externally threaded portion 60, an enlarged bore portion 61, a pair of diametrically opposite vertically extending slots 62, lapping element receiving vertically extending slots 63, and a lower bore portion 64.

65 A washer 65 is received within the recess portion 60 against the upper outer portion of the members 53, and a threaded annular plug 66 is threaded in the holder 56 for retaining the latter washer in place. Slidably supported within the shaft 31 and the tubular member 48 is a piston rod 67 which is adapted under conditions as will soon be apparent to control the expansion of lapping elements toward and contraction away from the surface of the work 9 to be lapped.

70 Within the bore portion 61 is an annular block 68 having a sliding fit within the bore. The

block 68 comprises threaded apertures 69 aligned with the pair of slots 62, and a pair of centrally aligned apertures 70 and 71, the aperture 70 being of larger diameter than the rod 67 and receiving the end portion of the rod 67 which is pivotally connected by a pin 72 to the block 68. The aperture 71 is of substantially the same diameter as a rod 73 fitted therein and extending axially of the holder 56. The rod 73 is secured to the block 68 by a pin 74, so as to be 10 guidably supported thereby for true central vertical reciprocatory movement. Slight pivotal movement of the end of the rod 67 about the pin 72 is permitted by the large aperture 70 for allowing self-centering action of rod 67. The member 73 has a lower flange portion 75 and is adapted to serve as a mandrel for the lapping tool 30. A pair of pins 76 are threaded in the apertures 69, and they protrude through the vertical guiding slots 62, threaded rings 77 being in 20 adjustable threaded engagement with the threaded portion 60 to limit the upward movement of the rod 67, extension 73, and the block 68.

25 Fixed to the lower end portion of the rod section 73 is a lapping element positioning member 81 comprising a cylinder slidably fitted within the bore 61 of the tool 56 and seated upon the flange 75. The upper end portion of the cylinder 81 is attached to the rod section 73 by a pin 82. The peripheral portions of this cylinder 30 are provided with arcuately spaced tapering recesses 80', having inner surfaces 80 inclined with respect to the axis of the rod section 73, into which extend lapping element supports 78. Each support 78 has a lapping stone or other lapping element 79 comprising suitable lapping material, mounted on its outer side and is provided with an inclined opposite side portion which conforms with and is seated upon the inclined surface 80 of the corresponding recess 80' in 35 which it is disposed. The recesses 80' register with the slots 63 of the tubular portion of tool and the supports 78 have portions radially shiftably mounted in these slots with the extremities of the supports guided by the end walls of the 40 slots. The lapping elements which extend through the slots 63 may be variably extended beyond the outer periphery of the tubular portion of the tool by axially upward movement of the cylinder 81, these lapping elements and their supports being normally yieldably urged inwardly 45 by spring members 84 secured to the tool by screws 85.

50 The upper end portion of the rod 67 is received within a lower recess of a tubular member 86 of H-shaped cross section having an internal partition which separates its interior into upper and lower recesses respectively. The reduced end portion 91 of a piston rod 87 which imparts vertical movement to the rod 67 is accommodated in the upper recess of this tubular member. The tubular member 86 is received within a sleeve 88 having an inwardly extending flange 89 at its upper end. A pin 90 extending through registering apertures in the member 86, sleeve 88 55 and rod 67 serves to attach these parts together. Mounted on the reduced end portion 91 of the piston rod 87 is a rolling contact thrust bearing unit 92 which includes a series of ball bearings interposed between upper and lower vertically 60 aligned race members which are disposed within the sleeve 88 and freely rotatable relative to the latter as well as to the reduced end portion 91 of the rod 87. These ball races are held between a shoulder located at the upper end of the re- 75

duced section 91 and a washer which is secured to the latter by nuts 93. The ball races extend radially beyond the shoulder of the piston rod 87 and the upper extremity of the top race is 5 engaged by the radial flange 89 of the sleeve 88 as illustrated in Fig. 2. With this construction the piston rod 87 may be relied upon to shift the rod 67 axially of the tube 31^a while the latter is rotating and without requiring the piston rod 87 10 to rotate. Relative rotation between the piston rod 87 and the actuating rod 67 is accommodated by the bearing 91 which coacts with the sleeve 88 and its flange 89 to apply an upwardly directed force on the rod 67, and with 15 the tubular member 86 to apply a downwardly directed force thereon.

A ball bearing 95 has one of its race members supported by the rod threaded portion 31^a and detachably secured thereto by a nut 96. The 20 other race member of the bearing 95 supports an annular member 97 which has an annular groove 98 within which the outer race of the bearing 95 fits.

The annular member 97 is detachably secured 25 by bolts 99 to a pressure cylinder carrying member 100. The member 100 comprises a pressure cylinder portion 101 and a partially threaded counterbore portion 102. Within the cylinder 101 is a piston 103 which is secured to the upper 30 end of the rod extension 87 and which is adapted to be moved vertically by the admittance of fluid pressure, preferably air pressure, through conduits 104 and 105 communicating with the cylinder 101 above and below the piston 103 respectively. A flanged tubular gland part 106 is received by the portion 101 of the member 100, and provided with annular sealing ring members 107 and 108 through which the piston rod 87 extends. An annular washer 109 is arranged 35 within the counterbore portion 102 to hold the sealing members 107 and 108 in leak-proof engagement with the gland part 106. The washer 109 is held in place by an externally threaded sleeve 110 surrounding the nut 96 and threaded 40 in the counterbore 102.

When rotation is imparted by the shaft 39 to the lapping elements 79 through the shaft 31, the piston 103 and rod 87 do not rotate for relative rotation between the piston rod 87 and the operating rod 67 is accommodated by the bearing 92 and the loosely fitting members 86 and 88 and the piston is restrained from rotating by engagement of the piston rings of the piston 103 with the cylinder 101. When the piston 50 103 is forced downwardly by fluid pressure admitted through the upper conduit 104 the rod portions 31 and 73 are simultaneously moved until the pins 76 contact the lower extremities of the slots 62 at which time the lowered lapping element positioning member 81 allows the springs 84 to contract the members 78 and 79. As fluid pressure is admitted through the lower conduit 105 and the fluid pressure above the 55 piston is exhausted through the upper conduit 104, the piston and the rod 67 are raised until the pins 76 strike the adjustable rings 77 during which time the member 81 forces the elements 79 outwardly by reason of its inclined surface. This controllable expansion and contraction of the lapping elements 79 permits removal and insertion of the lapping tool into the cylinder of the work 9 and the adjustable ring 77 facilitates selective predetermining of the extent to which the lapping elements are expanded,

thereby accurately predetermining the finished diameter of the work operated upon.

Rotative movement is imparted to the lapping tool, independently of the driving gear 33 and the adjustable movement of the piston within the cylinder 20, by a suitable power source such as the motor 111 detachably secured by bolts 112 to the carriage 14. The motor has a drive shaft 113 which is keyed at 114 to an eccentric member 115 supporting a ball bearing inner race 10 member 116 and ball bearings 117 which are interposed between the race member and a split outer race member 118. The outer member 118 comprises an extension arm portion 119 and a cap portion 120 detachably secured together by 15 bolts 121, the arm portion 119 being pivotally connected at 122 to the member 100.

During operation of the apparatus, the motor 111 drivingly reciprocates the lapping tool, preferably at a rate approaching a vibratory order 20 while the tool is rotated by the gear 33 about an axis extending in the general direction of the reciprocatory movement of the tool. The lapping tool may be raised and lowered to bring it out of and into lapping relationship with the 25 work during such reciprocatory and rotative movements or the latter may be discontinued while the tool is being moved toward and away from the work. Movement of the tool into and out of lapping relationship with respect to the 30 work may be accomplished by shifting of the carriage 14 by the action of the piston and cylinder 20 which may be supplied with fluid pressure medium through the conduits 23 and 24 under manual or automatic control. When it is 35 desired to subject the lapping tool to a stage of reciprocation in addition to that produced by the motor 111 and while the tool is rotating, the piston and cylinder 20 may be relied upon to reciprocate the carriage 14 and the lapping tool in 40 unison throughout a long stroke and at a slower rate than that of the reciprocatory movement produced by the motor 111. This may be accomplished by suitably alternately admitting fluid medium to the respectively opposite ends of the 45 cylinder 20 through the conduits 23 and 24, and alternately exhausting fluid medium therefrom.

With reference to the operation of this embodiment of the invention, when it is desired to remove the work from lapping receiving relationship with the lapping tool, the prime movers 43 and 111 are preferably shut off. Fluid pressure is then admitted by any suitable automatic or manual means through the conduit 104 to cause the lapping elements to be contracted, and 50 fluid pressure, preferably air pressure, is exhausted from the upper side of the piston within the cylinder 20 and fluid pressure admitted through the conduit 24 to move the carriage 14 upwardly for carrying the lapping elements up- 55 wardly in their contracted condition without putting any surface marks on the work. When the tool holder 75 is in its lower position and the carriage 14 is in its upper position, the lapping elements 79 and members 78 may be conveniently removed, if desired.

Following the raising of the lapping tool out of lapping engagement with the finished work, another motor block or another cylinder to be lapped may be positioned for receiving the lapping tool. Fluid pressure is then admitted through the conduit 23 to force the carriage 14 downwardly to place the lapping elements 79 within the cylinder to be lapped. Then fluid pressure is admitted through the conduit 105 to 60 65 70 75 80 85 90 95 100 105 110 115 120 125 130 135 140 145 150 155 160 165 170 175 180 185 190 195 200 205 210 215 220 225 230 235 240 move the tool holder 75 upwardly to expand the lapping elements into lapping receiving relationship with the work at a predetermined lapping pressure. The prime movers 43 and 111 are then started to respectively rotate and to oscillate through the eccentric 115 in short strokes the lapping tool 30, during which movement the piston 103 and the rod extension 107 do not rotate. If desired for purposes of production, the lapping elements can be contracted and the tool removed from the work and inserted into a bore of another piece of work and then expanded without discontinuing the rotation and reciprocation of the tool.

15 While the prime movers 43 and 111 are in operation, it is desirable to control the carriage 14 by imparting comparatively long vertical reciprocatory travel to the carriage to cause the lapping tool 30 to also reciprocate with the carriage while maintaining the lapping elements 79 in lapping contact with the work 9. This reciprocatory movement of the carriage 14 is preferably controlled by admitting fluid pressure alternatively to opposite ends of the cylinder 20

25 from the conduit 22 and the conduit 23 by any suitable automatic or manually controlled valve mechanism. The lapping elements 79 will thereby be simultaneously rotated and also reciprocated in short and long strokes during the lapping operation, resulting in a very efficient lapping apparatus.

Various modifications and changes may be effected in the illustrated applications without departing from the spirit of the invention or from the scope of the appended claims.

What we claim is:

1. Lapping apparatus including a support; a tool operating shank rotatively and reciprocatively mounted on said support and adapted to be drivingly rotated and reciprocated relative to said support during operation of said apparatus; a lapping tool head attached to said shank having a plurality of expansibly and contractably mounted lapping elements and including means for variably positioning said lapping elements; and mechanism for controlling said lapping element positioning means including a section carried by said shank and tool head and rotatable therewith, a section carried by said support, and a coupling between said sections so constructed and arranged as to accommodate substantially free rotation of said shank and tool head carried section with respect to said support and said support carried section during operation of said apparatus; and means for drivingly simultaneously reciprocating said shank and said tool head and rotating the same relative to said support.

2. Lapping apparatus including a support having a journal bearing therein; a tubular tool operating shank rotatively and reciprocably shiftably mounted in said journal bearing for rotative and reciprocative movement relative thereto and adapted to be drivingly rotated during operation of said apparatus; mechanism for drivingly reciprocating and rotating said shank a lapping tool attached to said tubular shank having a plurality of expansibly and contractably mounted lapping elements and including means for variably positioning said lapping elements; and mechanism for controlling said lapping element positioning means including a rod axially shiftably mounted within said tubular shank, and an actuating member movably carried by said reciprocating mechanism, and a rolling contact thrust bearing coupling between said actuating member and said rod so constructed and arranged as to accommodate substantially free rotation of said rod with respect to said actuating member during operation of said apparatus.

3. Apparatus including a frame structure; a support reciprocably mounted on said structure; a tool operating shank rotatively and reciprocatively mounted on said support and adapted to be drivingly rotated during operation of said apparatus; a lapping tool attached to said shank having a plurality of expansibly and contractably mounted lapping elements and including means for variably positioning said lapping elements; means including a driving member carried by said support for reciprocating said tool relative thereto at a rate of substantially vibratory order; means for reciprocating said support relative to said frame structure at a lower rate; mechanism for controlling said lapping element positioning means including a connecting member having one end operatively connected therewith and carried by said shank and rotatable with the latter, an actuating member carried by said tool reciprocating means, and a coupling between said actuating member and the other end of said connecting member so constructed and arranged as to accommodate substantially free rotation of said connecting member with respect to said actuating member during operation of said apparatus; and means for drivingly simultaneously reciprocating said tool relative to said support at said vibratory order and said support relative to said frame structure at said lower rate during rotation of said tool.
